[57] CLAIM

The ornamental design for a belt wench crank assembly, as shown and described.

DESCRIPTION

FIG. 1 is a isometric view of a belt wench crank assembly, showing my new design;

FIG. 2 is a left end elevation view of the belt wench crank assembly;

FIG. 3 is a right end elevation view of the belt wench crank assembly;

FIG. 4 is a front elevation view of the belt wench crank assembly;

FIG. 5 is a rear elevation view of the belt wench crank assembly;

FIG. 6 is a top view of the belt wench crank assembly; and,

FIG. 7 is a bottom view of the belt wench crank assembly.
